United States Patent Office

Des. 224,227

Patented July 11, 1972

224,227

HEATER

Joseph R. Mango, Midlothian, Ill., assignor to
Sunbeam Corporation, Chicago, Ill.

Filed Feb. 2, 1970, Ser. No. 21,210

Term of patent 14 years

Int. Cl. D23—03

U.S. Cl. D23—122

Fig. 1.

Fig. 3.

Fig. 2.

Fig. 4.

Fig. 5.

Fig. 6.

FIG. 1 is a perspective view of a heater showing my new design;

FIG. 2 is an enlarged side elevational view thereof, the opposite side being a mirror image;

FIG. 3 is a greatly enlarged fragmentary view of the grill which covers the front of the heater as best seen in FIGS. 1, 4 and 6;

FIG. 4 is a top plan view of the heater;

FIG. 5 is a rear elevational view thereof; and

FIG. 6 is a bottom plan view thereof.

I claim:

The ornamental design for a heater, as shown and described.
